UNITED STATES PATENT OFFICE.

HARRY F. WOERNLEY, OF PITTSBURGH, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

YIELDING COUPLING-SUPPORT.

1,090,185.

Specification of Letters Patent. Patented Mar. 17, 1914.

Application filed July 1, 1911. Serial No. 636,529.

To all whom it may concern:

Be it known that I, HARRY F. WOERNLEY, a citizen of the United States, residing at Pittsburgh, in the county of Allegheny and 5 State of Pennsylvania, have invented new and useful Improvements in Yielding Coupling-Supports, of which the following is a specification.

This invention relates to car couplers, and 10 more particularly to a yielding support therefor.

It has heretofore been proposed to provide a yielding support for the draw-bar, so that the car coupler is normally held level 15 in position for coupling, but when cars are coupled up, the support is adapted to yield for vertical movement of the draw-bar and coupler and thus prevent undue strain and wear in passing over uneven track and the 20 like.

In prior devices of the above character, the draw-bar is adapted to rest on the yielding support, and where a draw-bar of the type adapted for radial movement is employed, it will be seen that the yielding support must be designed to permit of this 25 radial movement.

The principal object of my invention contemplates mounting the yielding support for 30 the coupler on the draw-bar, so that the same is entirely independent of the mechanism for supporting and for permitting radial movement of the draw-bar, thus providing a simple, compact, and cheaply constructed device 35 of this character.

In the accompanying drawing, Figure 1 is a vertical section taken at a point intermediate the car center sills, showing a radial draw-bar and coupler with my improvement 40 applied thereto and Fig. 2 an enlarged elevational view of a portion of the draw-bar, showing the yielding coupler support in section.

As illustrated in Fig. 1 of the drawing, 45 a draw-bar 1, pivoted for radial movement, is mounted between the car center sills 2, and the coupler head 3 is pivotally mounted on the draw-bar 1 for vertical movement by means of a pivot pin 4. Integral with and 50 extending substantially vertically downward from the coupler head 3 is an arm 5

and preferably integral with the pivot end of the draw-bar is a spring pocket or casing 6.

A heavy coil spring 7 is mounted in the 55 casing 6 and a spring plate 8 is adapted to engage the outer end of the spring. A buffer bolt 9 passes through a central aperture in the spring plate 8 and an aperture in the rear end wall of the casing 6. Said bolt is 60 provided with a rounded head 10 adapted to engage with the inner face of the arm 5, and the opposite end of the bolt is screw threaded for a nut 11 adapted when screwed up to hold the parts in position. 65

It will now be evident that the tension of the spring 7 acting through the bolt 9 serves to normally maintain the coupler head level in position for coupling, while permitting a yielding vertical movement of the coupler 70 head when coupled up, so that in passing over uneven track or in other cases where a vertical movement is required, the coupler head may move on its pivot either above or below the normal center line of the coupler without imposing a strain on the parts. 75

Having now described my invention, what I claim as new and desire to secure by Letters Patent, is:—

1. The combination with a pivoted draw-bar and a coupler head pivoted to said draw-bar, of a vertically depending arm carried by the coupler head and a spring actuated buffer mounted on said draw-bar and adapted to engage said arm for yieldingly resisting 85 vertical movement of the coupler head from normal position.

2. The combination with a draw-bar and a coupler head pivoted to said draw-bar, of a casing integral with the pivot end of the draw-bar, a spring mounted in said casing, an arm carried by the coupler head, and a buffering member subject to the compression of the spring for engaging said arm to resist vertical movement of the coupler 95 head.

In testimony whereof I have hereunto set my hand.

HARRY F. WOERNLEY.
